UNITED STATES PATENT OFFICE.

RODNEY F. LUDLOW, OF SPRINGFIELD, OHIO.

DESIGN FOR A CAR-CO尤LING DRAW-BAR.

SPECIFICATION forming part of Design No. 24,895, dated November 12, 1895.

Application filed April 15, 1895. Serial No. 545,819. Term of patent 14 years.

To all whom it may concern:

Be it known that I, RODNEY F. LUDLOW, a citizen of the United States, residing at Springfield, in the county of Clark and State of Ohio, have invented a certain new and original Design for Car-Coupling Draw-Bars, of which the following is a specification, reference being had therein to the accompanying drawings.

Figure 1 is a side elevation of a car-coupler draw-bar, showing my design; and Fig. 2 is a cross sectional view of the same, taken on the line *y y* of Fig. 1.

The leading feature of my design consists of a draw-bar having the shape or configuration as shown.

The letter A refers to the head of a draw-bar and the letter B to the shank thereof. The head is formed or fashioned with a corrugated contour consisting of raised surfaces C and depressed intermediate surfaces D. In the cross-section shown in Fig. 1 this particular contour is further seen to be formed on the inner sides as well as the outer sides of the head. The thickness of the metal is substantially uniform throughout the corrugated portions, as also clearly seen in that figure. These

corrugations blend into the vertical bead E of the head and into the rear wall F of the head. The lower portion G of the head also harmonizes with this corrugated contour by being formed as shown in Fig. 2. The shank B is also of corrugated contour, as shown at H and I, which designate the raised and depressed surfaces. These raised and depressed surfaces extend also to and form part of the head, as seen at H' and I'. At the corners J of the shank the raised surfaces are fashioned to form about two-thirds, more or less, of a circle and blend into the depressed surfaces I. This configuration also carries the idea of substantially parallel walls on the inner and outer sides, and to this end the corners J have a longitudinal opening K.

What I claim is—

The design for a car coupling draw bar, here- in shown and described.

In testimony whereof I affix my signature in presence of two witnesses.

RODNEY F. LUDLOW.
